A. H. SKAER

MOTOR

Filed Feb. 24, 1920

Attorney

UNITED STATES PATENT OFFICE.

ARTHUR H. SKAER, OF DENVER, COLORADO, ASSIGNOR TO THE DENVER ROCK DRILL MANUFACTURING COMPANY, OF DENVER, COLORADO, A CORPORATION OF DELAWARE.

MOTOR.

Application filed February 24, 1920. Serial No. 360,696.

To all whom it may concern:

Be it known that I, ARTHUR H. SKAER, a citizen of the United States, residing at Denver, in the county of Denver and State 5 of Colorado, have invented certain new and useful Improvements in Motors, of which the following is a specification.

The present invention relates to motors operated by an expansive motive fluid, preferably air. One of the primary objects is to provide an improved structure that has certain structural advantages, as will herein-after appear, and is provided with means that will permit the necessary adjustment 10 of the parts in order to insure the non-binding action of the piston, while maintaining the necessary snug fit thereof.

A further and important object is to provide a structure in which a high degree of 15 efficiency can be obtained under different fluid pressures.

In the accompanying drawings:—

Figure 1 is a longitudinal sectional view through the preferred embodiment of the 20 invention,

Figure 2 is a cross sectional view on an enlarged scale.

Figures 3 and 4 are longitudinal sectional views through different forms of the interchangeable bushings that may be employed.

Similar reference numerals designate corresponding parts in all the figures of the drawings.

In the embodiment disclosed, a cylinder member is provided comprising a barrel 5 having a detachable head 6. The barrel is provided with a piston chamber 7, and the head 6 has a chamber 8 aligned with the chamber 7. A bushing 9 is located within 35 the cylinder member and bridges the joint between the barrel 5 and head 6, being provided with an external flange 10 that is clamped between the two members. The bushing extends into the chamber 7 and also 40 into the chamber 8, its rear end being tapered as shown at 11, so that said rear end is substantially free of the walls of the chamber 8. In the illustration, it may be explained that 45 this taper has been greatly exaggerated in

order that it may show. As a matter of 50 fact, it is relatively slight. The bore 13 of the bushing constitutes a reduced extension of the piston chamber 7.

The piston employed consists of a head 14 operating in the chamber 7, and provided 55 with oppositely disposed extensions 15 and 16, said extensions corresponding in size and shape, so that the piston is reversible and either end may be used as the hammer head. The rear extension 15 operates in the bore 60 13 of the bushing, while the front extension is adapted to strike against the rear end of a drill steel, as 17 placed in the chuck, designated generally by the reference numeral 18.

Motive fluid from any suitable source is 65 delivered to a longitudinal passageway 19 formed partly in the head 6 and partly in the barrel 5. The front end of the passageway 19 terminates in a port 20 in the front end of the cylinder member, and an annular 70 groove 21 formed on the extension 16 is adapted to move into and out of communication with the port 20 so as to permit the motive fluid to pass into the front end of the piston chamber 7 in advance of the 75 piston head 14, as illustrated in Figure 1.

The passageway 19 also has a lateral port 22 in communication with an annular groove 23 formed in the periphery of the bushing 9, and this annular groove 23 has communication 80 through a plurality of radial ports 24 with an internal groove 25 in the walls of the bore 13 of said bushing. The rear extension 15 of the piston has an annular 85 groove 26 that is adapted to move into and out of register with the groove 25 and affords communication between said groove and the piston 7 in rear of the head 14. An exhaust passageway 27 is in communication with the central portion of the piston chamber 7, and 90 is adapted to be crossed by the head 14. In order to supply motive fluid to the rear end of the rear extension 15, a plurality of longitudinal ports 28 are formed through the walls of the bushing 9, and constitute a 95 means of communication between the rear end of the piston chamber 7 and the rear portion of the piston chamber 8. The rear

end of the bushing 9 is spaced from the adjacent wall of the head in order to allow for the said communication. A small port 29 affords constant communication between 5 the channel 23 and the rear end of the piston chamber. This passage insures at all times the initial operation of the piston, irrespective of its position when the motive fluid is admitted to the machine.

10 The operation of the structure is substantially as follows. When air or other motive fluid is admitted to the passageway 19, assuming the piston in the position shown in Figure 1, this motive fluid will pass from 15 the port 20 through the channel 21 to the front end of the piston 7, and operating against the front face of the piston head 14, will drive the piston rearwardly. The exhaust behind the piston is open through 20 the port 27, as shown. As the piston approaches the rearward end of its stroke, the channel 26 will come into communication with the groove 25, while the port 20 will be cut off by the enlarged terminal 25 portion of the extension 16. When this takes place the piston head 14 has crossed the exhaust port 27, so that the chamber 7 in advance of the head is opened to said exhaust. The motive fluid now passes through 30 the ports 22, channel 23, ports 24, groove 25 and channel 26 into the piston chamber 7, behind the head 14, and a portion of this fluid will pass through the longitudinal passageways 28 to the rear end of the chamber 8. The piston will consequently be driven 35 forwardly and its entire area will be acted upon by the motive fluid. The employment of a bushing 9 separate from the other parts is important from a structural standpoint, 40 inasmuch as it permits the formation of the various ports and passages with ease and economy. It has been found also that by having the bushing a separate part and allowing a slight space between its rear end 45 and the head wall, as shown, it will adjust itself to the piston, avoiding any binding action due to the "cocking" of the piston. Another very material advantage is that it permits the use of interchangeable bushings 50 with the ports 24 at different distances from the rear end of the piston chamber. Experience has demonstrated that where the ports are at a fixed distance, while they will prove efficacious for one pressure, if 55 employed for a different pressure there is a loss of effectiveness. Thus in the embodiment illustrated, if the set of ports 24 are placed one-half inch from the front end of the bushing, as shown in Figure 3, the 60 arrangement is highly satisfactory for a low pressure of say sixty pounds. On the other hand, if high pressure of approximately one hundred and ten pounds is utilized, then the ports 24 should be placed farther 65 from the front end of the bushing, as for

example fifteen-sixteenths of an inch, as illustrated in Figure 4. This may be explained by the difference in the action of the air under different pressures. Where the air pressure is low, it requires more time 70 to act upon the piston than where the pressure is high. As a consequence with the low pressure and the ports near the front end of the bushing, it will be obvious that the channel 26 will come into communication 75 with the channel 25 sooner, and the pressure of the live air will have a greater length of time to build up behind the piston head and rear extension. Furthermore when the piston is returning the momentum 80 or returning energy of the hammer is such that it is carried well back toward the face of the bushing against this low pressure, permitting practically the maximum travel 85 of the hammer. With high pressure, however, the action is much quicker, and if high pressure were used through ports close to the end of the bushing the hammer would be stopped sooner and consequently would not obtain its full stroke. With the structure 90 therefore, it will be obvious that instead of a different machine for different pressures, it only requires the change of the bushings.

From the foregoing, it is thought that the 95 construction, operation and many advantages of the herein described invention will be apparent to those skilled in the art, without further description, and it will be understood that various changes in the size, shape, proportion and minor details of construction, may be resorted to without departing from the spirit or sacrificing any of the advantages of the invention.

Having thus fully described my invention, what I claim as new, and desire to secure by Letters Patent, is:

1. A motor comprising a cylinder member having a piston chamber, and a bushing fixedly and removably located in the cylinder member and having a reduced bore in communication with the piston chamber, said bore forming an extension chamber, a piston having an active pressure surface in the piston chamber, and a reduced extension operating in the bushing and having a similarly facing pressure surface, and means for distributing motive fluid to the piston chamber outside the bushing to operate against the pressure surface of the piston in said chamber and ports for simultaneously delivering a portion of said motive fluid from the piston chamber to the outer end of the bushing bore and against the said pressure surface of the piston extension in said bore.

2. A motor comprising a cylinder member having a piston chamber and a bushing fixedly and removably located in the cylinder member and having a bore in communication with the piston chamber and

- forming an extension chamber, a piston in the piston chamber having a reduced extension operating in the bushing, and means for supplying motive fluid through the bushing to the bore thereof and thence to the piston chamber in advance of the bushing, said piston extension having means for controlling the said passage of the motive fluid from the bore to the piston chamber, 5 and said bushing having ports for permitting the return passage of such fluid from the piston chamber to the outer end of the bushing bore and against the piston extension.
- 10 3. A motor comprising a cylinder member having a barrel and a removable head, provided with aligned chambers, a bushing in the chambers and clamped between the barrel and the head, a piston operating in the barrel chamber and having a reduced extension in the bushing, said bushing having transverse fluid supply ports, said piston having means for affording communication between the ports and the barrel chamber, 20 and said bushing having longitudinal passageways independent of the said communication afforded by the piston for directing motive fluid delivered into the barrel chamber therefrom into the head chamber.
- 25 4. A motor comprising a cylinder member having a piston chamber and an extension chamber communicating with the piston chamber, a piston in the chamber having an extension in the extension chamber, means controlled by the extension for supplying motive fluid to the piston chamber, and means in communication with the piston chamber for maintaining a constant supply of fluid thereto.
- 30 5. A motor comprising a cylinder member having a piston chamber and a bushing in the member having a bore forming an extension chamber, and a piston in the chamber having an extension in the extension chamber, said bushing having a fluid supply port controlled by the piston for admitting fluid to the chamber, and said bushing having an initial fluid supply port in constant communication with said chamber.
- 35 6. In a motor, the combination with a cylinder having a piston chamber, of a piston operating in the chamber and having a surface against which the motive fluid acts to move said piston, and means for supplying motive fluid to the chamber to operate against said surface including devices adapted to vary the distance between the point of inlet of such motive fluid and the said face when the piston is at one limit of its stroke.
- 40 7. In a motor, the combination with a cylinder member, of a piston operating therein and having an extension, and interchangeable bushings adapted to be placed in the cylinder and having ports that are respectively at different distances from the inner 45 ends of the same, said extension being adapted to operate in the bushing placed in the cylinder and controlling the supply of fluid delivered through the ports thereof.
- 50 8. In a motor, the combination with a cylinder member, of a piston operating therein and having an extension provided with a groove, and interchangeable bushings adapted to be placed in the cylinder and respectively having ports that are at different distances from the inner ends of the same, said extension operating in the bushing placed in the cylinder and the groove thereof moving into and out of connection with the ports of such bushing.
- 55 9. In a motor, the combination with a cylinder member, of a bushing therein having an annular groove in its periphery and a plurality of longitudinally disposed open ended passageways, means for supplying motive fluid to the groove, said bushing having transverse ports between the longitudinal passageways and opening into the groove, and a piston operating in the cylinder member and having a reduced extension that operates in the bushing and is provided with a groove that communicates with the transverse ports.
- 60 10. In a motor, the combination with a cylinder member, having a motive fluid supply port, of a piston that operates in the cylinder member and having a reduced extension, a bushing adapted to be detachably mounted in the cylinder member and surround the piston extension, said bushing being provided with a port therethrough and being so constructed that said port may be located at different distances from the end of the bushing and still communicate with the supply port of the cylinder member, and means carried by the piston extension for controlling the passage of motive fluid from the bushing port to the cylinder member in advance of the bushing.
- 65 11. In a motor, the combination with a cylinder member having a motive fluid supply port, of a piston that operates in the cylinder member and having a reduced extension, a bushing member adapted to be detachably mounted in the cylinder member and surround the piston extension, one of said members having a groove that communicates with the supply port and said bushing member having a transverse port of less extent than the groove, and means carried by the piston extension for controlling the passage of motive fluid from the bushing port to the cylinder member in advance of the bushing.
- 70 12. In a motor, the combination with a cylinder member having a motive fluid supply port, of a bushing therein having an external annular groove between its ends that is in constant communication with the supply port, said bushing also having transverse 75 80 85 90 95 100 105 110 115 120 125 130

inlet ports therethrough that are in constant communication with the groove and are of less diameter than the width thereof, and a piston operating in the cylinder member and provided with a piston extension that operates in the bushing and controls the ports therein to intermittently prevent in-

gress of the motive fluid into the bushing.

In testimony whereof, I affix my signature in the presence of two witnesses.
